UNITED STATES PATENT OFFICE.

FRANKLIN SCHNEIDER, OF CLEVELAND, OHIO, ASSIGNOR TO THE WHITELY EXERCISER COMPANY, OF CHICAGO, ILLINOIS, A CORPORATION OF ILLINOIS.

EXERCISING APPARATUS.

SPECIFICATION forming part of Letters Patent No. 691,295, dated January 14, 1902.

Application filed January 31, 1898. Serial No. 668,552. (No model.)

To all whom it may concern:

Be it known that I, FRANKLIN SCHNEIDER, a citizen of the United States, residing at Cleveland, in the county of Cuyahoga and State of Ohio, have invented certain new and useful Improvements in Exercising Apparatus, of which the following is a specification.

My invention relates to elastic exercising apparatus; and it consists in various arrangements of parts whereby is secured adjustability of the tension of elastic elements, an adjustability of the relative length of some of the component parts of the elastic medium or elements.

15 The invention also provides means for securing compound movements along peculiar and variable lines.

The invention further consists in certain details of construction fully described, and 20 pointed out in the claims and illustrated in accompanying drawings, in which—

Figure 1 is a view of one form of the exercising apparatus, showing at the same time in diagram certain of the compound movements. Fig. 2 is a simple form showing one of the adjustable features. Figs. 3 and 4 show details of the automatic clasp for the base-cord. Fig. 5 shows the base-cord in one of the adjusting positions. Fig. 6 is a detail. 25

30 Figs. 7 and 8 show other forms of friction-relieving shoes or clasps.

Like letters of reference indicate like parts throughout.

My exercising apparatus consists of two 35 elastic or resilient cords looped about each other, as shown in Fig. 2, or the equivalent, as shown in Figs. 1, 3, 4, 7, and 8, one of the cords being suitably supported to some solid portion—such for instance, as the wall, floor, 40 or ceiling of a room—(it may be vertically disposed or at any other suitable angle) and the other cord (both of which are preferably elastic or resilient) being so adjusted and attached to the first-named cord as to be able to pull outwardly from the supports against some point between the supports. This point may be midway or near either one or the other supports or in any intermediate position, not only to suit the convenience or fancy of the operator,

but primarily to secure such automatic change 50 in the alinement of the movement as is found to be desirable in the best performance of any well-designed exercising apparatus. An apparatus of this character which can exert its tension in only one line is found far inferior 55 to one which, while being able to perform the unilinear action, may at the same time be so adjusted as to be made to automatically vary the point from which the muscular exertion is resisted, thereby calling into action a constantly-varying number of muscles and a varied combination of muscular action. This valuable feature of the apparatus is secured by simply varying the point at which the cords are looped about each other from the 60 center toward either of the points of support, as will be readily understood from Fig. 1. In all these figures, A represents the base-cord; B B, the handled bearing cord or cords; a, the points at which the base-cords are anchored. a', a'', and a³ (see also Fig. 5) represent the various support-engaging devices whereby attachment may be effected to one or the other of the anchors aa. It will readily be understood that these support-engaging 65 devices may be on both ends of the base-cord, if desired. The handles may be seen at D, Fig. 2, and may be of any suitable form. 70

In Fig. 6 may be seen one of the adjusting support-engaging devices, which is formed 80 by a heavy metal clasp C. These clasps also may be seen in the other figures. This clasp is placed around the cords at their point of crossing and is U-shaped when so placed. A heavy swage then closes the points of the U, 85 tightly grasping the cords.

It has been found that when the exerciser in the form shown in Fig. 2 is used the cords, which are usually covered by textile fabric, are rapidly worn by abrasion at their points 90 of contact. In Figs. 3, 4, 7, and 8 are shown details of devices which I have employed to relieve this abrasion and friction. The form shown in Figs. 7 and 8 provides loose flanged tubular slides g, more or less loosely encircling the base-cord A. To these are secured a friction-relieving loop, through which the handled cord B may be easily drawn back 95

and forth with a minimum friction, and the bell-shaped mouths *g*' insure the cords against wear at the edges.

The form of loop or junction device shown 5 in Figs. 1, 3, and 4 is not necessarily tubular in shape, but consisting rather of a loop *i*, passing back of the base-cord *A* and carrying at its free end a pulley *I* in one or another plane with reference to the base-cord *A*. The 10 back portion of loop is suitably curved to more properly fit the base-cord *A* when the same is pulled to a considerable angle, (see Fig. 1,) and the loop is also provided with a 15 clasping device consisting of a dog *n*, provided with thumb-pieces *n' n'*. This dog is provided in center region with a pin or pins *o*, coöperating with the inclined slot *o'* shown in the clasp *i*. It will be seen on close inspection that this dog, coöperating with the 20 inclined slot *o'*, constitutes an automatic locking device between the clasp *i* and the base-cord *A*, the action of which is as follows: When the handled cord *B* is pulled vigorously, the base-cord *A* by increase of its 25 tension grows smaller and smaller throughout its length and within the clasp *I*, allowing the dog *n* to slide farther and farther downward, the inclined slot *o'* forcing it closer to the back wall of the clasp *i*. When 30 again a lesser tension is existing in the cord *A*, it will be found to be tightly impinged between the dog *n* and the back wall of the clasp *i*, securely holding the parts in position. It will furthermore be seen that this 35 position can be at once changed and the dog forced against the base-cord *A* at will of the operator by evident manipulation of the dog *n* by means of thumb-pieces *n' n'*.

While it is designed to use all of the various features described in the connection shown, yet it is obvious that some may be used without the others, and the invention extends to such use.

I have spoken of one cord being "looped" 40 about the other. By this term I mean to in-

clude any equivalent construction, and have suggested some equivalent constructions in the drawings hereto attached.

Having thus fully described the character of my said invention, what I desire to claim 50 and secure by Letters Patent is—

1. An exercising apparatus consisting of two elastic or resilient cords adjustably connected together at or near their centers, the one suitably supported at or near its ends 55 forming a base-cord, the other provided at its ends with operating-handles, and an adjustable connection between the two cords so that the point of connection may be varied for compounding the motion.

2. An exercising apparatus consisting of two elastic or resilient cords, one connected at or near its end to a suitable support, the other adjustably connected with the first cord so that the point of connection may be varied, 60 an intermediately-connecting part provided with a friction-relieving device for one of the cords.

3. In an exercising apparatus, an elastic cord or element supported at or near its ends, 70 forming a base-cord, a loop encircling said base-cord at any suitable point between the supports, and carrying a second cord, and an adjustable clamping device for clamping the two cords together in different relative positions.

4. In an exercising apparatus, an elastic cord supported at or near one of its ends, the other end provided with a plurality of support and engaging devices for adjusting the 80 tension, said cord forming a base-cord, a looped part encircling the cord at any suitable point between the supports, and a handled cord lying in a plane normally transverse to the base-cord, and held by the said loop.

FRANKLIN SCHNEIDER.
